FENCE CHARGING CIRCUIT

Lee A. Woolley, Kokomo, Ind., assignor to Kings-
ton Products Corporation, Kokomo, Ind., a cor-
poration of Indiana

Application February 7, 1946, Serial No. 646,043

2 Claims. (Cl. 171—97)

1

This invention relates to a fence charging circuit for supplying periodic high voltage surges to a fence for the purpose of retaining live stock in the enclosure defined by the fence, and particularly to a fence charging circuit embodying safety elements automatically operative to prevent the application of a voltage to the fence which would be dangerous to humans or live stock contacting such fence.

Fence charging circuits have heretofore been known wherein the entire circuit was supplied from a relatively low voltage D. C. source, such as a six volt storage battery. As is customary in such circuits, an electrically operated interrupter periodically established current flow through the primary of a step up transformer. A charging condenser was connected in parallel to the contacts of the interrupter. Periodic making and breaking of the primary circuit and the accompanying charging and discharging of the condenser produced a high voltage surge potential in the secondary of the transformer which was applied to the fence. While such surges were of sufficient intensity to exert the desired restraining shock on any live stock attempting to pass over the fence, the duration of the surge was so limited that there was no possibility in the normal operation of the circuit that the shock thus received could be fatal to either live stock or humans.

With the extension of alternating current power to many farms, there arises a need for a fence charge controlling circuit which will conveniently operate from the customary household current supply which is normally 110 volts at 60 cycles. The fence charging circuits heretofore produced for operation on alternating current have embodied two outstandingly detrimental features: first, in the event that there was a failure of the alternating current power, the fence would be de-energized and accordingly the live stock could escape from the fenced enclosure until the alternating current supply was reestablished; secondly, and more important, it has been repeatedly observed that charged fences are particularly susceptible to being struck by lightning during a storm. Under such conditions, with the conventional alternating current supplied fence charging circuit, the current surge produced by the lightning may not only melt and secure the contacts of the interrupter together but also may produce various shorting connections within the fence charging circuit or to the metallic casing in which the control apparatus is contained, the combined result of which is the continuous ap-

2

plication of the 110 volt alternating current to either the primary or secondary of the step up transformer. Accordingly, a continuous voltage of appreciable magnitude is thus accidentally applied to the fence and a continuous shock can be delivered to any live stock or human coming in contact with the fence in such condition. Under such conditions, the resulting shock could well be fatal.

Accordingly, it is an object of this invention to provide an improved fence charging circuit which may be operated on alternating current with little, if any, possibility of accidental application of a dangerous voltage on the fence.

Another object of this invention is to provide a fence charging circuit normally operable from an alternating current supply but including connections for a low voltage D. C. circuit supply, such as a battery, and a relay automatically operable to energize the fence from the D. C. source upon the occurrence of a failure of the A. C. source supply.

A particular object of this invention is to provide an improved fence charging circuit wherein a wave trap or filter is provided in the output of the fence charging circuit intermediate such circuit and the fence, and said filter is effective to substantially eliminate the application to the fence of any dangerous voltages of the frequency of the alternating current source.

The specific nature of this invention, as well as other objects and advantages thereof, will become apparent to those skilled in the art from the following detailed description of the annexed sheet of drawings which, by way of preferred example only, illustrates one specific embodiment of the invention.

On the drawings the single figure is a circuit diagram of fence charging circuit embodying this invention.

As shown on the drawing:

A fence charging control circuit in accordance with this invention comprises a pair of A. C. input terminals 2 adapted to be connected to a suitable source of alternating current power, such as 110 volts, 60 cycle current, by means of a conventional plug 4. The terminals 2 are in turn connected thru suitable fuses 3 to the primary winding 6 of an input transformer 8. A line surge protective device 12 may be connected across the primary 6. Such device may constitute any one of several well known forms and in general includes a limited width air gap connection to ground which breaks down upon the occurrence of a surge voltage applied to either of the terminals 2.

The secondary 10 of transformer 8 is connected across the input terminals of a full wave rectifying bridge 14 of dry disk-type rectifying elements 16. The secondary winding 10 of transformer 8 is also connected to directly energize the coil 20 of a change over relay 18. The negative terminal 22 of the D. C. output side of rectifier bridge 14 is connected to ground through a ballast resistor 24. The positive terminal 26 is connected to one contact 28 of the relay 18. A bypass condenser 30 is also connected across the D. C. output terminals 22 and 26 of the rectifier bridge 14. The condenser 30 is of large capacity to insure the substantial elimination of all harmonic components from the D. C. output of rectifying bridge 14.

A pair of D. C. input terminals 30 are provided, one of which is connected through a switch 32 to ground, and the other of which is connected to the second fixed contact 34 of relay 18. Any suitable source of low voltage D. C. power, preferably a storage battery of substantially the same voltage as developed by rectifier bridge 14 may be connected to D. C. input terminals 30.

The movable contact 36 of relay 18 is connected by conductor 38 to the input of the charging unit or surge generating unit 40. The surge generating unit 40 may comprise any one of several well known forms of such apparatus and in general comprises a step-up transformer 42 having the primary winding 44 thereof periodically energized through the conductor 38 by means of the interrupter unit 46, the contacts 48 of which are connected in series with primary winding 44. Interrupter 46 comprises an oscillating member similar to that shown and described in U. S. Patent No. 1,585,318, issued May 18, 1926, to A. W. Tupper. It will be understood that the interrupter 46 is only shown schematically in Fig. 1 and as shown by the afore-mentioned patent will include a solenoid (not shown) for producing its oscillating movement which solenoid is periodically energized by the same current flowing through contacts 48.

The contacts 48 of interrupter 46 when closed complete a circuit to ground so that the closing of these contacts completes a current supply circuit for primary winding 44 from either rectifier bridge 14 or D. C. input terminals 30, depending upon the position of movable contact 36 of relay 18. A charging condenser 50 is connected across contacts 48 so as to be charged by the inductive effect of primary winding 44 upon the opening of contacts 48. Movable contact 36 of relay 18 is biased by a spring 37 to normally maintain such movable contact in engagement with fixed contact 34. However, when the A. C. input terminals 2 are connected to a suitable source of A. C. power, the coil 20 of relay 18 is energized and the movable contact 36 of the relay is then moved into engagement with the fixed contact 28, completing a power supply circuit for the surge generating unit 40 from the output of the rectifying bridge 14.

From the aforescribed connections, it will be apparent that the surge generating unit 40 is supplied from the A. C. source so long as A. C. power is available. Upon failure of A. C. power for any reason, the movable contact 36 of relay 18 returns to its normal position and immediately connects the D. C. input terminals 30 and the associated battery (not shown) to supply power for the operation of the surge generating unit 40.

The secondary winding 52 of the step up transformer 42 is directly connected to a binding post 54 and the connection from the fence to be charged (not shown) may be made to binding

post 54 when the weather conditions have been particularly dry. A second binding post 58 is provided which is connected to secondary winding 52 through a resistor 60 and the connection from the fence (not shown) may be made to binding post 58 for normal or wet weather conditions. Suitable protective gap devices 60 may be provided, respectively, connected between binding posts 54 and 58 and ground.

10 To afford an indication of the proper operation of the surge generating unit, a lamp 59 of the neon type may be connected between binding post 58 and ground through a series resistor 64. It will be understood that lamp 59 flashes each time that a surge voltage is applied to the fence.

15 The other end of secondary winding 52 of step up transformer 42 is connected to ground through a filter or wave trap circuit 67, here shown as comprising the parallel connected inductor 65 and condenser 68. The filter 67 may take any one of a variety of several well known forms but in accordance with this invention, the characteristics of filter 67 are selected so as to produce a very high impedance to the flow of current in

20 the output of the surge generating unit of the same frequency as that of the alternating current source; further, the characteristics of filter element 65 are selected to yield a very low impedance to current of the frequency corresponding to the surges generated by the surge generating unit 40.

25 The operation of the fence charging circuit embodying this invention is deemed obvious in view of the foregoing description. A D. C. current is supplied to the input of the surge generating unit 40 from either the D. C. input terminals 30 or the output of the rectifying bridge 14 dependent upon the existence of alternating current power across the A. C. input terminals 2. However, the current flow through the primary winding 44 of 30 step up transformer 42 occurs only while the contacts 48 of the oscillating interrupter 46 are closed or immediately following the opening of such contacts when the inductance of primary winding 44 produces a discharge through charging condenser 50. Thus each time that the oscillating interrupter 46 makes and breaks the D. C. circuit through the primary 44 of step up transformer 42, a surge voltage is produced in the secondary winding 52 which is applied to the fence 35 (not shown).

40 In the event that a shorting connection is produced anywhere within the circuit by lightning or other accident such that the A. C. voltage is supplied to either the primary or secondary circuit of step-up transformer 42, it is apparent that such A. C. voltage will also be applied to the fence. However, due to the high impedance of the filter element 67 to currents of the frequency of the A. C. source, the intensity of current flow of such 45 frequency that will occur upon the contact of livestock or humans with the fence will be reduced by filter 67 to a value below that which can prove harmful to either livestock or humans. Accordingly, circuit disarrangement produced by lightning or any other cause will not operate to impress a dangerous A. C. voltage on the fence. Furthermore, upon the failure of A. C. power for any reason, the automatic changeover relay 18 immediately functions to energize the surge generating unit from the D. C. source and thus insures that the fence is continuously charged. Restoration of A. C. power automatically cuts out the D. C. source.

50 It will, of course, be understood that various details of construction may be varied through a 55

wide range without departing from the principles of this invention and it is, therefore, not the purpose to limit the patent granted hereon otherwise than necessitated by the scope of the appended claims.

I claim as my invention:

1. A fence charging circuit comprising A. C. input terminals adapted to be connected to a source of alternating current, D. C. input terminals adapted to be connected to a source of D. C. current, rectifying means connected to said A. C. input terminals, surge generating means responsive to direct current for periodically producing high voltage surges, circuit means for supplying said surges to a fence independently of current from said alternating current source and said circuit means including filter means responsive to current of the frequency of said source but not to said high voltage surges for substantially eliminating current flow of the frequency of said source in said circuit means, and relay means normally connecting said surge generating means to said D. C. terminals and responsive to application of alternating current to said A. C. input terminals to disconnect said surge generating means from said D. C. terminals and to connect said surge generating means to said rectifying means.

2. A fence charging circuit comprising A. C. input terminals adapted to be connected to a source of alternating current, D. C. input terminals

nals adapted to be connected to a source of D. C. current, rectifying means connected to said A. C. input terminals, surge generating means responsive to direct current for periodically producing high voltage surges having a frequency different from the frequency of said alternating current source, a circuit adapted to supply said high voltage surges to a fence independently of current from said alternating current source, said circuit including a series connected filter having a high impedance at the frequency of said source and substantially negligible impedance to said voltage surges, a relay, and means for energizing said relay from said A. C. terminals, said relay being arranged to connect said surge generating means to said rectifying means when said relay is energized and to connect said surge generating means to said D. C. terminals when said relay is de-energized.
